ABSTRACT

A time delay relay of the type in which a semiconductor switching element is made conductive after a predetermined time by a RC time constant circuit so as to actuate a relay connected in series with the semiconductor switching element with respect to a power source. The RC time constant circuit is connected to the semiconductor switching element through a transistor element and, among leakage current of the semiconductor switching element, the current flowing through resistor of the RC time constant circuit is restrained to be low utilizing amplifying action of the transistor element, thereby enabling a delaying action for a long time period.

TIME DELAY RELAY

DISCLOSURE OF THE INVENTION

This invention relates to a time delay relay enabling a long delaying action. Such time delay relay that the relay therein is actuated by the voltage of a time constant circuit comprising a capacitor and resistor detected by such a switching element having a negative resistance characteristic as, for example, a silicon unilateral switch, a silicon bilateral switch, a silicon symmetric switch of the like is well known. Such kind of relay is featured in that its operation includes snap action and the relay can be self-retained without using relay contacts.

FIG. 1 shows a voltage-current characteristic of the above mentioned switching element, in which the element is completely turned on when voltage across the switching element is gradually increased and reaches the switching voltage V_s and, if a current greater than holding current I_h is caused to continue flowing thereafter, the switching element holds its conductive state. In this case, forward voltage drop of the switching element is V_f . This switching element is not brought into conduction unless a current of the magnitude I_s (switching current or break over current) is caused to flow there through just before firing thereof.

FIG. 2 shows an example of the relay circuit utilizing the above mentioned switching element. In this drawing, Q is a switching element, X is a relay coil, D_1 and D_2 are diodes, R_1 is a resistor, R_t and C_t are time limiting resistor and capacitor, respectively, and E_1 and E_2 are D.C. power sources. E_1 has a voltage higher than the firing voltage V_s of the switching element and the time limiting resistor R_t and capacitor C_t are connected in series therewith. The resistor R_1 , diode D_2 and the switching element Q are connected in parallel to said capacitor C_t . The relay coil X, the diode D_1 and the element Q are connected in parallel to the power source E_2 (which is of lower voltage than V_s).

Upon application of power supply voltage, the voltage V_c across the time limit capacitor C_t is gradually increased. When the voltage V_c reaches the firing voltage V_s of the switching element Q, the element turns ON and thereby the relay X is actuated. At the same time, the charge on the capacitor C_t is discharged through the resistor R_1 , diode D_2 and switching element Q.

In the relay of such circuit as above, there arise the following problems:

a. In case the leakage current I_s just before firing of the switching element is large, such current will flow into the time limit resistor R_t causing a larger voltage drop to occur. This results in that the voltage V_c across the capacitor C_t will not be raised up to desired value and thus the switching element will not be conducted. This may cause failure of operation. On this account, the time limit resistor R_t cannot be made large in value and, consequently, the long delaying operation cannot be expected and the switching element utilizable is limited to an element that has a very small value of I_s .

b. The switching element Q is to be maintained in its conductive state by a continuous current mainly from the power supply voltage E_2 and larger than the holding current I_h . In case many ripples are included in the power supply voltage E_2 , the current flow may happen to be lowered below the holding current I_h and the switching element Q may become non-conductive, causing the relay to be turned OFF.

c. If the power supply is interrupted at a time t_2 (FIG. 4) shorter than the normal delaying time t_1 by any reason during time limiting operation (the condition in which the capacitor C_t is being charged and the element Q is not yet conducted), the voltage V_c across the time limiting capacitor C_t remains as charged without being discharged at all as shown by a broken line in FIG. 4. Thus, when the power supply is again switched on, the operation will be caused to begin at 10 the time shorter than the normal delaying time t_1 .

d. Even in case the power supply is interrupted at a time t_3 after the normal time limiting operation, the voltage V_c of the time limiting capacitor C_t cannot be decreased through discharging below the sum of the 15 forward voltage drop of the diode D_2 and the forward voltage drop V_f of the switching element, and subsequent delaying time is similarly influenced by this.

e. Such relationship that the voltage of source E_1 > voltage V_s of element Q > voltage of source E_2 is required, and two source voltages are also necessary. Furthermore, driving voltage of the relay cannot be made larger.

According to the present invention, the above mentioned problems in the time delaying relay can be solved by detecting the voltage rise at the time constant circuit by a switching element having a negative resistance characteristic inserted through a transistor.

It is a principal object of the present invention to provide a relay capable of actuating with a long delay time.

Another object of the invention is to provide a relay capable of actuating even with large leakage current of the switching element.

A further object of the invention is to provide a relay in which the timing capacitor discharges rapidly its charge even if the power supply is interrupted during the delay timing, and no adverse effect on the next timing operation will be caused.

It is a further object of the invention to provide a relay capable of normally operating even with a power supply voltage containing many ripples.

The present invention will be explained in connection with embodiments thereof with reference to the accompanying drawings, in which:

FIG. 1 shows a characteristic of a switching element;

FIG. 2 is a circuit of a conventional time delay relay;

FIG. 3 is an embodiment of the time delay relay circuit according to the present invention;

FIG. 4 and 5 show operational characteristics;

FIG. 6 shows an equivalent circuit of the switching element; and

FIG. 7 is another embodiment of the present invention.

Referring to FIG. 3 showing an embodiment of the present invention, a time constant circuit comprising a timing resistor R_t and a timing capacitor C_t is connected in parallel with a D.C. power supply E. The junction point between said resistor R_t and capacitor C_t is connected to the base of a first transistor T_1 . The transistor T_1 has a collector connected to the positive side of the power supply through a resistor R_1 and also to the negative side of the power supply through another resistor R_2 . The emitter of the transistor T_1 is connected to the base of a second transistor T_2 through a resistor R_3 . A relay coil X is connected between the collector of the transistor T_2 and the positive side of the power supply. The emitter of the transistor T_2 is connected to an anode of the switching element Q with

three terminals which has a negative resistance characteristic. The cathode of the element Q is connected to the negative side of the power supply. A capacitor C_1 is connected between the gate of the switching element Q and the base of the transistor T_2 .

Operation of this circuit is as follows.

Upon application of the power supply voltage, the timing capacitor C_t begins to charge and, when voltage V_c across the capacitor C_t reaches the firing voltage V_s of the switching element Q, the latter detects this through the base and the emitter of the respective transistors T_1 and T_2 so as to be conducted. Thus, base current will flow and the transistors T_1 and T_2 , thereby the transistors are made to be conductive so as to drive the relay X.

The features of the present circuit is as follows:

a. Even in case of a large leakage current I_s of the switching element Q, only the base current divided by an actual amplification factor will flow on account of amplifying action of the transistor (the current flowing through the timing resistor corresponds to the base current), and thus most of the leakage current I_s will flow through the delay coil X while little current will flow through the timing resistor R_t . As a result, the current I_s will produce no voltage drop across the timing resistor R_t and, therefore, the voltage V_c across the timing capacitor C_t will fully rise sufficiently higher and thus there occurs no failure in the relaying operation. It is, therefore, possible to select a large value for the timing resistor R_t and a long time delaying can be achieved.

b. In the case of a large ripple current, the conduction of the switching element Q is maintained by means of discharging charge of the capacitor C_1 even when the current flowing through the switching element Q is lowered below the holding current I_h . Accordingly, the switching element Q does not become non-conductive not only at the time when the supply voltage contains large ripple but also in case of half-wave rectified supply voltage or full-wave rectified supply voltage. This is also applicable to the case of momentary OFF state of the power source.

c. In case the power supply is interrupted during the timing operation, that is, at the time t_2 shorter than the normal delay time t_1 , adverse biasing between the base and the collector of the transistor T_1 is released and P-N junction is established between such base and collector of the transistor. Thus the charge on the timing capacitor C_t is discharged through the base, the collector of the transistor T_1 and the resistor R_2 . This discharging is shown by a broken line in FIG. 5. The resistor R_2 has no effect on normal time delaying operation and provides a compensation for withstand voltage of the transistor T_1 .

d. In case the power supply is cut off after the timing operation, that is, at the time point t_3 , residual charges left in the timing capacitor C_t will completely discharge through the resistor R_t , R_1 and R_2 as shown by a solid line in FIG. 5. If the discharging path does not consist of only pure resistance components, such complete discharging cannot be expected. Accordingly, the next delaying operation will be quite normal and an excellent repeating time characteristic can be obtained.

e. If withstand voltage of the transistors T_1 and T_2 is selected to be sufficiently large, the power supply

voltage can be made large irrespective of the voltage V_s of the element Q.

f. Even if a surge appears in the power supply line during the timing operation, any erroneous operation can be prevented by the capacitor C_1 .

g. The transistors T_1 and T_2 are connected in the form of two stages and a large base current for the relay driving transistor T_2 is taken out of the resistor R_1 without directly passing the current through the timing resistor R_t . This causes a very large coil current for the relay X to flow. This allows uses of a relay having a large coil capacity and a timing resistor whose value is very large. Even in this case, the transistors T_1 and T_2 can be maintained in complete conductive state.

15 FIG. 6A shows an equivalent circuit of the switching element having negative resistive characteristic, and FIG. 6B shows terminals thereof.

FIG. 7 shows another embodiment of the present invention, in which polarities of the transistors are reversed and also the polarity of the switching element Q is reversed. The capacitor C_1 is connected between the gate and the anode of the switching element Q. Operation of the circuit is similar to that of the circuit shown in FIG. 3.

25 What is claimed is:

1. A time delay relay comprising a first series circuit including a timing resistor and a timing capacitor, a second series circuit including a pair of resistors connected in parallel with said first series circuit, a D.C. source connected across each of said series circuits, a first transistor element having its base connected between said timing resistor and said timing capacitor and its collector connected between the two resistors in said second series circuit, and a second transistor element having its base connected to the emitter of said first transistor element, a relay winding connected between the collector of said second transistor element and the resistor end of said first series circuit, and a semiconductor switching element connected between the emitter of said second transistor element and the capacitor end of said first series circuit.

2. A time delay relay as defined in claim 1 wherein a discharging resistor is connected between the collector of said first transistor element and the capacitor end of said first series circuit, so that a discharging by-pass for residual charges of the timing capacitor is formed through the base and emitter of the first transistor element and said discharging resistor when the timing operation is interrupted before completion of the timing period.

3. A time delay relay according to claim 1, in which said semiconductor switching element is a three terminal semiconductor switching element, and a capacitor for maintaining conduction of the switching element is connected between the gate electrode of said semiconductor switching element and the base of the transistor element.

4. A time delay relay according to claim 1 in which said semiconductor switching element is a three terminal semiconductor switching element, and a capacitor for maintaining conduction of the switching element is connected between the gate electrode and the anode electrode of the switching element.
